UNITED STATES PATENT OFFICE.

ARTHUR M. CROSBY, OF BOSTON, MASSACHUSETTS.

SELF-LEVELING BERTH.

SPECIFICATION forming part of Letters Patent No. 252,079, dated January 10, 1882.

Application filed June 17, 1881. (No model.)

To all whom it may concern:

Be it known that I, ARTHUR M. CROSBY, of Boston, in the county of Suffolk and State of Massachusetts, have invented certain Improvements in Self-Leveling Berths, of which the following is a specification.

This invention relates to self-leveling berths or other structures for ships; and it has for its object to provide such a berth which shall occupy the minimum of space, and which shall combine simplicity of construction and economy in cost.

To this end my invention consists in a self-leveling berth suspended by four oblique rods or rigid hangers arranged in pairs, the rods of each pair extending diagonally from a single point in the center of one end of the berth, and pivoted independently to points of support beyond the transverse axial line and on opposite sides of the longitudinal axial line of the berth, as I will now proceed to describe and claim.

Of the accompanying drawings, forming part of this specification, Figure 1 represents a side elevation of a self leveling berth embodying my invention. Fig. 2 represents an end view of the same. Fig. 3 represents a top plan view, showing the arrangement of the hangers.

The same letters relate to the same parts in all the figures.

30 In the drawings, A represents a berth, which may be of any desired size and construction.

h h' h' represent rigid hangers, preferably wrought-iron rods, by which the berth A is suspended from the ceiling of the cabin or other fixed overhead support, c. The hangers h h' h' are arranged in pairs, each pair being pivoted to a single point, a, in the center of one end of the berth, the rods composing each pair diverging diagonally therefrom, as shown 35 in Fig. 3, and extending obliquely to points of support e beyond the transverse axis of the berth, as shown in Fig. 1, the extremities of said rods being pivoted to said points of support. I prefer to make the distance between

40 the points of support e of one pair of hangers (in this instance the hangers h h) about equal to the width of the berth, and to place the points of support of the other pair of hangers somewhat nearer the longitudinal axial line of 45 the berth, so as to avoid all danger of friction or chafing of the hangers upon each other during the movements of the ship; but in all cases

the points e of each pair of hangers are placed upon opposite sides of the longitudinal axial line of the berth, while by the previously-described arrangement of the hangers, as will be seen, the points e of one pair of rods are upon the opposite side of the transverse axial line from the points e of the other pair.

By the described mode of suspending the 60 berth the effect of double-crossed hangers is secured, and the hangers being rigid, the tendency to rotate or swing in either direction is counteracted and a rocking movement imparted to the berth irrespective of the motion 65 of the ship. The berth is therefore adapted to occupy the minimum of space without danger of swinging so far as to touch the wall upon either side during the pitching of the vessel, and the weight of the berth and its occupant 70 being entirely below the points of suspension, no springs are required to be interposed between the berth and the wall or floor to counteract the quick oscillation which would otherwise result from the vessel's movement.

In operation, during the fore-and-aft motion of the vessel, when the stern rises, the rigid hangers on the opposite end of the berth tend to push the berth toward the stern and the hangers on the other end tend to pull the berth 80 in the same direction. The fore-and-aft movement of the vessel is therefore compensated. In the same way, during the rolling motion the rods h h' on one side tend to push the berth in one direction, while the rods h h' on the 85 other side tend to pull the berth in the same direction, thus compensating the rolling motion, and the hangers being freely movable upon their pivots, the berth is maintained in a level position at all times. The elasticity of 90 the hangers when arranged as described prevents any shock resulting from the movements of the vessel and partially compensates any vertical movement imparted to the berth.

The hangers may be used as an aid in entering the berth, and said hangers may be bent to avoid a projecting knee or other obstruction without interfering with the operation of the berth.

It will be seen that my improved berth is 100 extremely simple in construction, and requires no expensive adjuncts either above, below, or around the same. It may therefore be easily and cheaply put in place or removed therefrom.

when desired, and economically maintained in working order.

5 *s s* represent bolts arranged on the back side of the berth, and adapted to engage with orifices in the walls or partitions at the ends to lock the berth and prevent its swinging motion whenever desirable—as, for instance, when a person is getting into or out of the berth. The bolts are operated by a lever, *l*, pivoted 10 at *v* to the side of the berth, the bolts being pivoted to the lever at *w w*. The lever is provided with a handle projecting above the berth, and is held to secure the bolts, when the berth is locked, by a ratchet, *b*, on the side of the 15 berth, the lever being engaged with either of the teeth of the ratchet by its own elasticity, causing it to spring inwardly against the ratchet-teeth. It will be seen that the bolts are adapted to prevent any horizontal or vertical independent movement of the berth.

20 It is obvious the described mode of hanging

the berth *A* is equally applicable to tables, settees, or other structures for ships which it may be desirable to make self-leveling.

Having thus described my invention, I 25 claim—

A self-leveling berth or other structure for ships, suspended by four oblique rods or rigid hangers arranged in pairs, the rods of each pair extending diagonally from a single point 30 in the center of one end of the berth, and pivoted independently to points of support beyond the transverse axis and on opposite sides of the longitudinal axis of the berth, as set forth.

In testimony whereof I have signed my name 35 to this specification, in the presence of two subscribing witnesses, this 14th day of June, A. D. 1881.

ARTHUR M. CROSBY.
